UNITED STATES PATENT OFFICE.

WILLIAM B. JUPP, OF NEW YORK, N. Y., ASSIGNOR TO INTERNATIONAL MOTOR COMPANY, OF NEW YORK, N. Y., A CORPORATION OF DELAWARE.

DESIGN FOR A RAILWAY-CAR BODY.

Application filed November 26, 1927. Serial No 24,285. Term of patent 14 years.

To all whom it may concern:

Be it known that I, WILLIAM B. JUPP, a citizen of the United States, residing in the borough of Manhattan of the city of New York, in the State of New York, have invented a new, original, and ornamental Design for Railway-Car Body, of which the following is a specification, reference being had to the accompanying drawings, forming a part hereof.

Figure 1 is a plan view of a car constructed in accordance with the present design.

Figure 2 is a view in elevation showing the design of the car in Figure 1.

Figure 3 is an end elevation taken from the left in Figure 2.

I claim:

The ornamental design for a railway car body as shown.

This specification signed this 22nd day of November, A. D. 1927.

WILLIAM B. JUPP.
